HERMETICALLY SEALED JUNCTION MEANS

Clarence L. Wallace, Jr., Topanga, and Edward J. Diebold, Palos Verdes Estates, Calif., assignors to International Rectifier Corporation, El Segundo, Calif., a corporation of California

Application October 8, 1958, Serial No. 766,032

15 Claims. (Cl. 317—234)

This invention relates to rectifiers for alternating electric current.

It is well known that a rectifier containing a crystal of silicon which is free from internal stresses, from structural defects, and from surface contamination has very valuable rectifying properties. These properties can rarely be fully utilized because inherent in conventional rectifiers is the likelihood of either contaminating the crystal in manufacture, or stressing the crystal when the device is in use, in such a manner that the rectifying capacity thereof is seriously reduced.

Contamination of the surface of a silicon crystal need not be great in order to almost completely destroy the ability of the crystal to operate as a rectifier. Only very low concentrations, of molecular order, are enough to cause an excessive increase in reverse current. It has been found that even the most carefully conducted surface treatment operations tend to leave harmful impurities on the crystal, and that the more the crystal is treated the more impurities are deposited on the crystal.

In addition because silicon rectifiers are particularly suited for rectifying heavy currents, they ordinarily are put in installations where the crystal and its supporting structure are subjected to large temperature fluctuations, and these fluctuations cause undesirable mechanical stresses. These stresses tend to destroy the rectifying ability of the device.

It is an object of this invention to provide a rectifier in which, in the entire course of its manufacture, the crystal is exposed to contamination only one time; that is, in a single manufacturing step. During the time the crystal is exposed, it is surrounded and protected by a very pure protective atmosphere, whereby a minimal amount of impurities can reach the crystal. Furthermore, the materials surrounding the crystal at the time of exposure are not of a type which would tend to contaminate it.

Still another object of the invention is to provide a structure in which the crystal is largely isolated from structural stresses which result from temperature changes resulting from the passage of high currents through the rectifier.

Still another object of this invention is to provide a rectifier which can be made of easily and inexpensively fabricated parts, and in which the manufacturing operations are simple, and do not require complex or complicated procedures for minimizing contamination of the crystal.

This invention is carried out by installing a rectifying element comprising a semi-conductor such as crystal of silicon upon a base plate which provides one terminal for the rectifier, and connecting a stud to the other side of the crystal to constitute the other terminal of the rectifier. The crystal is hermetically sealed by surrounding the rectifier and its stud with an insulating ring which is mounted atop a tubular structure, the tubular structure being attached at one of its ends to the base plate and at its other end to the insulating ring whereby lateral expansions and contractions of the base plate are taken up in the tubular

structure, thereby relieving lateral expansion forces in the device. A flexible diaphragm interconnects the stud and the insulating ring, thereby relieving axial forces in the device.

5 A related feature of this invention resides in the method of assembling this rectifier, whereby the elements described above may be assembled in a furnace in stacked relationship with bonding solders and the like between them, and brazed together in the presence of a protective atmosphere. By this means, the silicon crystal is exposed to operations only once during the assembling process, and contamination is minimized by the protective atmosphere. Because the resulting structure is hermetically sealed by this operation, no additional contaminants ever

10 reach the crystal.

The above and other features of this invention will be fully understood from the following detailed description and the accompanying drawings, of which:

Fig. 1 is a side elevation partly in cut-away cross-section 20 of a rectifier according to the invention;

Fig. 2 is a cross-section taken at line 2—2 of Fig. 1;

Fig. 3 is a fragmentary cross-section showing another means of installing a silicon wafer in the rectifier structure of Fig. 1;

25 Fig. 4 is a side elevation partly in cut-away cross-section showing two of the rectifiers of the type shown in Fig. 1 mounted in tandem and connected to supporting structure; and

Fig. 5 shows another means for mounting a plurality of 30 rectifiers of the type shown in Fig. 1.

Fig. 1 illustrates a rectifier assembly 10 which includes a rectifier element 11. The rectifier element is enclosed in a surrounding structure and is mounted to a base plate 12 which forms a part of the surrounding structure.

35 The rectifier 11 includes a semi-conductor shown as a silicon wafer 13. This wafer consists essentially of pure intrinsic silicon, and is bonded to base plate 12 by a layer 14 of a solder which includes N-type impurities. N-type impurities are defined as metallic elements which

40 are negative compared to elements in the fourth column of the periodic table of the elements, preferred elements for this purpose being selected from the fifth column, for example, arsenic, antimony and bismuth. The solder comprises a low concentration of these relatively negative elements in a carrier. The carrier consists of a metal 45 which has a relatively stable outer electron shell, examples being gold, copper and silver. As is well known, these carrier metals serve as a bonding agent between metal plates. Under heat treatment some of the N-type impurities will migrate into the silicon wafer so as to form a surface of N-type silicon with a boundary between what will become N-type silicon, and intrinsic silicon. A preferred N-type solder consists essentially of silver and a minor amount of antimony.

50 55 A layer 15 of a silicon-aluminum alloy serves to bond a metal disc 16 to the wafer 13. Layer 15 is an alloy of silicon and aluminum. The aluminum is present to provide a P-type impurity for the silicon crystal. A P-type impurity is defined as a metal which is more positive than the elements in the fourth column of the periodic table of the elements. Aluminum is a P-type metal. Gallium, 55 indium and thallium are several other examples. These and aluminum fall in the third column of the periodic table of the elements which column contains the preferred P-type metals for this use. As is well known, under heat treatment, the P-type impurity migrates into the intrinsic silicon, and results in the formation of a surface layer of P-type silicon with a boundary between the intrinsic silicon and the silicon with the P-type impurity.

60 As a result of the introduction of N-type impurities to one side of the crystal, and P-type impurities to the other, a rectifying crystal having the physical composi-

65

tion of N-type, intrinsic, and P-type silicon in contiguity in that order is obtained, which is suitable for rectifying alternating electric current. For the purpose of definition, the rectifying element 11 is defined as comprising wafer 13 and the two solder layers 14 and 15.

The metal disc 16 is preferably made of the same material as the base plate so as to minimize stresses on the wafer 13 which could result from heating the rectifier if the base plate 12, disc 16, and a wafer 13 attached to them were to have different thermal coefficients of expansion. Molybdenum is the preferred metal for both the base plate 12 and the disc 16, because the thermal expansion of molybdenum closely matches that of silicon. The rectifier element is not internally stressed to any significant degree when the rectifier is heated up with this arrangement, but it is pointed out that both solder bonds are more flexible than the plates and the disc on either side, so that shear stresses between the plate and disc and the crystal are largely taken up by the solder, and are not transmitted to the crystal.

An elongated stud 17 is bonded to the disc 16 by a layer 18 of silver solder. This stud has a circular section throughout its length, and terminates in a rod-like upper section 20. An advantage of this shape is that it can easily be formed on a header by a cheap fabrication process.

A tubular element 21 is ring-shaped and has a U-shaped radial cross-section. This section has a flat central bight 22 (which is therefore a flat annulus) and a pair of depending legs 23, 24. It is evident that these two legs are both tubes which have their free ends depending downwardly from the central bight. The lower ends of these legs are attached by solder rings 25, 26 to the base plate 12, with the rectifier element attached to the base plate, inside the tubular element.

An insulator ring 27 is placed atop the tubular element 21. Its upper and lower surfaces are metalized so that the ring can receive soldered connections. The ring is preferably made of a refractory material which does not dissociate at high temperature, such as aluminum oxide. The lower end of the insulating ring is bonded by a solder ring 28 to the central bight of the tubular member 21. An upper solder ring 29 is provided for joining the outer periphery of a diaphragm 30 to the upper surface of the ring.

Diaphragm 30 has a central web 32 with an opening 33 at the center. There is a small turned-down flange 34 in the diaphragm adjacent the opening which provides with the stud a depression for receiving solder 35 that bonds the diaphragm 30 to the stud.

A convenient means for connecting the rectifier into a circuit is to provide a metal cup 36 which is inverted so that its rim 37 fits into an annular depression 38 in the diaphragm 30. Solder 39 may be used to attach the rim of the cup to the diaphragm 30. The cup has an opening 40 at its central portion for receiving a grommet 41 which serves to attach a flexible terminal lead 42 to the cup. A cooling fin 43 may be bonded to the base plate by a layer 44 of solder, and the fin can then be used at the other terminal of the rectifier assembly, instead of the base plate, if desired.

In the construction shown in Fig. 1, the order of polarity upward from the base plate is N-intrinsic-P. It may be desired to reverse this polarity, and provide the order P-intrinsic-N. This is achieved by substituting in place of the rectifier element 11 in Fig. 1, a rectifier element 45, shown in Fig. 3.

Rectifier element 45 includes a silicon wafer 46 which is bonded to a molybdenum disc 47 on its bottom side by a layer 48 of P-type solder. Disc 47 is soldered to the base plate 12 by a layer of solder 49. A second molybdenum disc 50 is bonded to the upper side of the silicon wafer by a layer of N-type solder 50a.

The rectifier structure of either Fig. 1 or 3 can be manufactured by first stacking all of the elements

together. The solder for the joints will be provided as discs or rings, as appropriate. Then graphite weights are applied to hold the assembly together, and the weighted assembly is transferred to an oven having a hydrogen gas or inert gas atmosphere. The temperature is elevated so that the solders melt to make their joints, and so that the P-type and N-type impurities infuse into the silicon. The structure is then cooled and the rectifier is ready for use.

It will be noted that the atmosphere inside the ring is that of the furnace, and that after the solder bonds have been hardened, the same atmosphere remains in the hermetically sealed rectifier. This atmosphere protected the wafer from oxidation during the heating process, and after assembly, the surrounding structure isolates the wafer from any source of contamination. Furthermore, the metals within the structure are not the dissociative type, nor is the material of ring 27. No contaminants are likely to reach the wafer at all. Therefore this means of manufacture exposes the wafer only once, and then it is not exposed to any source of likely contamination.

The device shown can be adapted to many suitable structural applications. For example, in Fig. 4, a rectifier 51 of the type shown in Fig. 1 has a terminal lug 52 soldered thereto, instead of the flexible lead shown in Fig. 1.

A second rectifier 53 of the type shown in Fig. 1 has its cup soldered to a cooling fin 54 attached to the upper rectifier 51, while its own fin 55 is soldered to a hexagonal-headed stud 56 having a thread 57 thereon. As shown, the stud can be threaded into a tapped hole 58 in a bus bar 59. Persons skilled in the art will appreciate how stacks of rectifiers such as that shown in Fig. 4 can be made up of any desired length, and how the various fins may be used for electrical terminals in structures such as bridge circuits and the like. The structure of Fig. 4 can, for example, be used as one-half of a full-wave rectifier.

As an additional example, in Fig. 5 a pair of rectifiers of the type shown in Fig. 1 are illustrated connected in series. A spacer 60 holds the two fins apart, while a nut and bolt assembly 61 holds the fins in tight assembly, so as to properly space and firmly mount the two rectifiers. The terminal lead 62 of a rectifier 63 is connected by a nut and bolt assembly 64 to the fin 65 of another rectifier 66. The terminal lead 67 of rectifier 66 provides one terminal of series connection shown while another lead 68 may be attached to the fin 69 of rectifier 63, to complete provisions for electrical connections.

It will be observed that the silicon wafer is substantially protected against stresses in all directions because of the construction of the device. With respect to lateral stresses, the solder layers on each side of the wafer of semi-conductor material have less resistance to shear loads than the plates or other structures to which they bond the wafer. Therefore, when the base plate, silicon wafer, or stud heats up and causes lateral expansion in the region of the wafer, any differential movement will be taken up by the soft soldered bonds and little if any force will be exerted directly upon the silicon wafer.

Lateral forces resulting from the expansion of the base plate are also taken up by the tubular member 21. It is well known that the end of a tube can be expanded or contracted quite easily and without significantly distorting the tube at a distance significantly removed from the distorted end. Accordingly, when the ends of the tubular legs 23, 24 are expanded or contracted, little if any of this movement is communicated to the bight 22 so that the lateral expansion or contraction of the base plate has no substantial effect on the over-all structure, the tubular member acting to relieve them.

It is to be understood that other types of silicon junctions could have been provided, such as common P-N junctions where a crystal doped with one type of im-

purity is contacted by another type of impurity. The type of junction is completely variable, because the bonding materials can have either type of impurity therein, or even no impurity at all, and the wafer itself can be either intrinsic silicon, or either type silicon.

With respect to differential axial movements, the flexible diaphragm 30 acts as a weak link in the system and can easily absorb any differential movement between the outer portion of the structure and the inner portion.

It will therefore be seen that this rectifier comprises an inexpensive structure which is easily manufactured from conventional parts and which inherently provides an easy means of manufacturing a clean, uncontaminated rectifier in which the full capabilities of a semi-conductor such as a silicon crystal in power rectification can be utilized.

This invention is not to be limited by the embodiments shown in the drawings and described in the description, which are given by way of example and not of limitation, but only in accordance with the scope of the appended claims.

What is claimed is:

1. A hermetically sealed rectifier comprising: a conductive base plate, a rectifying element conductively mounted on said base plate; a stud conductively mounted on said rectifying element; a tube mounted to said base plate; an insulating ring mounted to said tube, said ring and tube surrounding said rectifying element; and a diaphragm extending between and connected to the stud and to the insulating ring, the diaphragm making a fluid-tight seal between the ring and stud, the base plate, tube and ring completing, with the diaphragm, a fluid-tight enclosure for the rectifying element.

2. A rectifier according to claim 1 in which the tube and ring are substantially circular cylinders.

3. A hermetically sealed current rectifier comprising: a base plate; a rectifying element mounted to the base plate in conductive contact therewith; a stud mounted to said rectifying element on the other side thereof from the base plate; a channel member having a pair of legs and a central bight, the channel member being attached by its legs to the base plate around the rectifying element, the bight being spaced from the base plate by the legs; an insulating ring mounted to the web of the channel member on the other side thereof from the base plate and surrounding the rectifying element; and a diaphragm extending between and connected to the stud and to the insulating ring.

4. A hermetically sealed rectifier comprising: a base plate with a flat surface; a semi-conductor wafer with a flat surface; a first metallic bond conductively mounting said wafer to the base plate in surface-to-surface relationship, the metallic bond having a shear strength less than that of the base plate and wafer; a tubular member attached to said base plate, surrounding the wafer; an insulating ring mounted to the tubular member on the opposite side thereof from the base plate; a stud conductively mounted to the wafer on the other side thereof from the base plate; and a flexible diaphragm interconnecting the insulating ring and the stud.

5. Apparatus according to claim 4 in which the insulating ring is made of refractory material, and the remainder of the rectifier is made of metal.

6. Apparatus according to claim 4 in which the tubular member has a U-shaped cross-section formed by 6 a central bight and two depending legs, the legs being tubular, and attached to the base plate.

7. Apparatus according to claim 6 in which the insulating ring is made of refractory material, and the remainder of the rectifier is made of metal.

8. Apparatus according to claim 4 in which the first metallic bond includes an N-type impurity, and in which the stud is mounted to the wafer by a metal plate to which it is bonded, a second metallic bond bonding said metal plate to the other side of the wafer and including a P-type impurity.

10 9. Apparatus according to claim 4 in which the first
metallic bond includes an N-type impurity, said first bond
mounting the wafer to the base plate by a first metal
plate, said first plate being conductively bonded to said
base plate, and in which the stud is mounted to the wafer
15 by a second metal plate; a second metallic bond bonding
said second metal plate to the other side of the wafer, and
including a P-type impurity.

10. A hermetically sealed rectifier comprising: a base

plate with a flat surface; a semi-conductor wafer with a flat surface; a first metallic bond conductively mounting said rectifying element to the base plate in surface-to-surface relationship, the first metallic bond having a shear strength less than that of the base plate and wafer; a tubular member attached to said base plate, said tubular member being generally cylindrical and having in cross-section a central bight and two tubular legs extending from the same side of said bight, said tubular legs being attached to said base plate; an insulating ring mounted to the bight of the tubular member; a stud conductively mounted to the rectifying element on the other side of the base plate; and a flexible diaphragm interconnecting the insulating ring and the stud and forming a fluid-type barrier therebetween; said stud being mounted to the rectifying element by means of a metal plate interposed therebetween which is bonded to the stud and to the wafer; and a second metallic bond bonding the metal disc to the wafer, said base plate, tubular member, insulating ring, diaphragm, and stud being continuous structures, continuously joined to form a fluid-tight structure.

40 11. Apparatus according to claim 10 in which the first metallic bond includes an N-type impurity and in which the second metallic bond includes a P-type impurity.

12. Apparatus according to claim 10 in which the first metallic bond includes a P-type impurity and the second metallic bond includes an N-type impurity.

45 13. Apparatus according to claim 10 in which the outer
periphery of the diaphragm has an annular groove there-
in, and in which a cup having a rim is inverted over the
diaphragm with its rim conductively bonded in the an-
50 nular groove whereby a first electrical connection can be
made through the cup, diaphragm, stud and metal plate
to the rectifying element, the base plate providing a sec-
ond connection.

14. Apparatus according to claim 13 in which a terminal lead is connected to the cup.

15. Apparatus according to claim 13 in which a cooling fin is attached to the base plate in heat-transfer relationship therewith.
